US00D749510S

(12) **United States Design Patent**
Liu

(10) **Patent No.:** **US D749,510 S**
(45) **Date of Patent:** **** Feb. 16, 2016**

(54) **USB CHARGER FOR ELECTRONIC CIGARETTE**

(71) **Applicant:** **HUIZHOU KIMREE TECHNOLOGY CO., LTD.**, Huizhou, Guangdong Province (CN)

(72) **Inventor:** **Qiuming Liu**, Huizhou (CN)

(73) **Assignee:** **HUIZHOU KIMREE TECHNOLOGY CO., LTD.**, Huizhou, Guangdong Province (CN)

(**) **Term:** **14 Years**

(21) **Appl. No.:** **29/525,778**

(22) **Filed:** **May 1, 2015**
